LIQUID PUMP

Juel D. Clevenger, Raytown, and Michael A. Waters, Independence, Mo., assignors to Cook Chemical Company, Kansas City, Mo., a corporation of Missouri

Filed Aug. 5, 1966, Ser. No. 3,356

Term of patent 14 years

(Cl. D24—1)

Fig. 1.

Fig. 2.

Fig. 3.

Fig. 4.

Fig. 5.

FIG. 1 is a bottom view of a liquid pump showing our new design;

FIG. 2 is a side elevational view thereof;

FIG. 3 is a top plan view thereof;

FIG. 4 is an elevational view showing one end thereof; and

FIG. 5 is an elevational view showing the opposite end thereof.

The tube shown fragmentarily in broken lines in FIGS. 2, 4 and 5 is for illustrative purposes only.

We claim:

The ornamental design for a liquid pump, as shown and described.
